UNITED STATES PATENT OFFICE.

CARL J. PIHL, OF NEW YORK, N. Y., ASSIGNOR OF ONE-HALF TO
ALEXANDER M. SUTHERLAND, OF SAME PLACE.

BACK-PEDALING BRAKE.

SPECIFICATION forming part of Letters Patent No. 623,928, dated April 25, 1899.

Application filed May 5, 1898. Serial No. 679,837. (No model.)

To all whom it may concern:

Be it known that I, CARL J. PIHL, a citizen of the United States, residing at New York, (Brooklyn,) in the county of Kings and State 5 of New York, have invented new and useful Improvements in Bicycle Brakes and Coasters, of which the following is a specification.

My invention relates to a new and improved bicycle-brake operated by the pedals and frictional devices for applying power to the wheel which will enable the pedals to be stopped while the wheel continues in rotation; and my invention consists of the parts and the constructions and combinations of parts 15 which I shall hereinafter fully describe and claim.

Reference is to be had to the accompanying drawings, forming part of this specification, in which similar letters and numerals of reference indicate like parts throughout the several figures.

Figure 1 represents a side elevation of my invention, with portions broken away, applied to a bicycle. Fig. 2 is a vertical sectional view of the same. Figs. 3, 4, 5, and 6 are modifications of the frictional devices to be hereinafter described. Fig. 7 is a side view of a brake to be hereinafter referred to.

In said drawings, A represents a disk which 30 is keyed or otherwise fixed to the crank-axle B, so as to revolve therewith and form the support or carrier for the clutch mechanism hereinafter specified. Opposing the disk A is a second or flanged disk C, which is fastened to said disk A by means of screws or other well-known devices, said disks A and C serving jointly to hold the sprocket-wheel D, which is made with a large central opening in place between them, the said disks having 35 also inwardly-projecting interlocking annular flanges c'd, whereby a strong, firm, and secure seat is formed between them to insure both disks being held rigidly together. The sprocket-wheel has a snug fit between the 40 disks, yet is free to revolve between them when the rider is coasting, and the disk C has a large opening in its center, in which is placed a loose ring E, from one side of which projects a stud, pin, or lug d', to which is connected an arm, rod, or link e, the opposite 45 end of which is adapted for connection with

a brake-shoe of any well-known form. In the present instance (see Fig. 7) I show this brake-shoe as consisting of an endless band 10 and interposed wear-plate mounted in a hanger 55 12, pivotally suspended and normally held away from the tire by means of a spring, as shown, described, and claimed in my former application, Serial No. 675,924, filed March 31, 1898; but other and well-known forms of 60 brake-shoes and suspending devices may be used with the present construction without departing from the spirit of my invention, the main object being to devise a simple means whereby the backward movement of 65 the pedals will apply the brake-shoe to the tire, and thus retard the forward motion of the wheel. In order that such motion may be properly and effectively transmitted, I employ a clutch mechanism, which I will now 70 disclose. This clutch mechanism comprises a roller or rollers operating in a tapered or converging recess between the sprocket-wheel and the opposing surface of the disks and between the disks and the opposing surface of 75 the ring. The clutch between the sprocket-wheel and disk unite the two, so that they may rotate together in the forward direction when propelling the wheel forward and disengage when the disk is moved backward, as 80 in coasting or back-pedaling. Wherever placed the effect is to produce a positive and strong clutch. The recesses may be in the disk, the sprocket-wheel, or the ring, and they contain the rollers, while the other or 85 opposing part is smooth to form frictional contact with the rollers. The part which carries the rollers is formed with the recesses 14, in the base of which is secured a block or piece of hardened steel 15, which serves as a 90 wear-plate and is made thicker at one end than at the other to provide a recess wider at one end than at the other. In each of these tapering recesses I place one or more rollers 16 or equivalent devices adapted to frictionally engage the smooth wall of the opposing member. From this arrangement it is manifest that when the crank-shaft is rotated by the pedals the sprocket-wheel will be carried in the same direction and the rollers 16 will 100 be moved into the smaller or contracted end of their recesses 14, so as to insure a strong and

positive clutch action between the sprocket-wheel and disks; but if the pedals are now held against rotation the disks A and C are also held, the sprocket-wheel is permitted to 5 continue its rotation, and the clutch-rollers move back into the deeper portions of their recesses, so as to remove the friction between the sprocket-wheel and the disks. In this latter condition the rider is free to coast with 10 the pedals stationary. If it is desired to apply the brake-shoe to the tire, a backward movement of the crank-shaft is transmitted to the disks A and C, and the rollers between them and the ring are now acted upon by 15 friction to cause them to ride into the reduced or contracted portion of their recesses, and thereby frictionally clutch and bind between the bearing-blocks or wear-plates 15 and the opposing surface of the ring. In other words, 20 as the disks are moved backward by back-pedaling the clutch or clutches between the loose ring E and the inner periphery of the disk C will act, their rollers being carried forward into the contracted portions of their recesses to form a clutch with the ring and imparting to this loose ring the backward movement of the disks and crank-shaft, resulting 25 in the bar, rod, or link e forcing the brake-shoe into contact with the tire.

30 In order to secure the loose ring E in place, I employ a ring F, internally threaded and adapted to screw into engagement with a threaded annular flange l, projecting from the disk A, said ring F having a peripheral flange 35 or lip m to engage a corresponding groove in the loose ring E, as shown in Fig. 2.

The rollers 16 of the clutches may act directly against the opposing surface of the disk, as shown at g, Fig. 1, or they may act 40 against an interposed loose plate h, which serves to take up the wear of the opposing frictional parts. The use of these plates, and they may be used wherever desired, permits me to dispense with an unusual hardening of 45 the surface of the disk or ring against which the rollers act. These plates h are curved to correspond with the curvature of the disks or ring, and they are enough shorter than the recesses 14, in which they operate, that they 50 move forward to clutch the opposing surface or move backward to relieve the same, as circumstances require.

In Fig. 1 I show a series of rollers in each recess, these rollers being of gradually-reducing diameters and being used in series for the purpose of dividing the frictional strain on them. If one roller only is used, it must stand all the strain, and there exists a liability of the roller being fractured or 60 broken because of the great strain upon it; but when two, three, or more rollers are used for each recess they form a corresponding number of points to which the strain is distributed, each roller, therefore, only resisting 65 a pressure proportionate to the whole number of rollers used. Instead, however, of using the rollers in series I may use them

singly with good effect. Thus in Fig. 3 I show single rollers in short tapered recesses, and if I desire to use but a single roller as 70 the clutch member for the entire disk or ring it will be best to employ a spring s, as shown in Fig. 3, for the purpose of holding the roller forward or into the more contracted portion of its recess and to prevent its rolling back 75 into the enlarged or wider portion of the recess by gravity as the roller is rising with its disk or ring in an ascending arc; also, it is not absolutely essential that the series of rollers should be of decreasing or increasing 80 diameters. Thus in Fig. 4 the rollers 4 are of uniform diameter, but used in series. To obtain the clutch effect, however, the recesses for such rollers should be divided by shoulders or offsets 17 into as many short tapering 85 spaces as there are rollers. The result accomplished, whether the rollers be in the ring or disk or between any two opposing surfaces, one of which must of necessity be a smooth unbroken surface, is substantially 90 the same in all cases. The same is substantially true when the form of clutch shown in Fig. 5 is used. In this instance, however, I dispense with rollers and substitute curved shoes or plates 18, the backs of which have 95 sockets in which one end of one or more bars or plates 19 are fulcrumed, the opposite ends of said bars being fulcrumed to the opposite clutch-surface.

Another modification is shown in Fig. 6, 100 where what I term a "cradle-piece" 20 is let into the recess in one of the clutch-surfaces and has an enlarged head 21, the outer surface of which is curved to correspond with the outer curvature of the disk or ring which 105 carries it and is normally substantially flush therewith. From the head 21 the cradle-piece is of reduced thickness and extends substantially at right angles and in a curved line, so that the central portion of its back or inner side contacts with and fulcrums upon the bottom wall of the recess in which the cradle-piece is placed, and its outer face forms, with the smooth surface of the ring, disk, or other opposing member of the clutch, a tapering 115 opening or cavity 22, in which a roller (or rollers) is placed. In this form of clutch when the disks and sprocket-wheel are rotating together in the same direction and approximately uniform speed the friction-surface 120 of the head 21 is out of close contact with the opposing friction-surface; but when the disk is held stationary or moved backward by the pedals, as before described, the roller is caused to roll forward into the contracted 125 part of its cavity, depressing the tail end of the cradle-piece, and thereby causing said piece to rock on its fulcrum in the base of the recess and the head end of the piece to be lifted into such intimate contact with the 130 opposing clutch-surface that the desired friction is produced between said surface and cradle-piece.

In each of the forms of clutches herein men-

tioned one of the clutch-surfaces, whether it be the ring, the disk, sprocket-wheel, or other part, will have a smooth and unbroken surface to be engaged by the other member of the clutch, whether said last-named member be the rollers, the shoes, or the cradle-piece.

In order that the sprocket-wheel may be fixed to the disk upon which it is mounted, which is desirable for persons just learning to ride, I provide a disk A with a lug or bearing *n*, within which a bolt *o* is mounted, the bolt being connected with a finger-piece *p*, by which it may be operated, whereby it may be thrust into a hole made in the sprocket-wheel to make a rigid connection between the said wheel and the disks, or said bolt may be retracted by a spring to disconnect the parts and allow them to operate in coasting or back-pedaling, as desired.

Having thus described my invention, what I claim as new, and desire to secure by Letters Patent, is—

1. In a bicycle, the combination of a disk fixed to the crank-shaft, a second disk fitted 25 sidewise against the first-named disk and made rigid therewith, said disks separated from each other at their peripheries to form an annular channel, a sprocket having an open center and with its inner periphery slidably fitted in said channel, a clutch mechanism between the disks and sprocket-wheel and normally holding them in frictional contact to enable the sprocket-wheel and disks to travel together in the same direction, and to 35 enable said sprocket-wheel to continue in motion when the disks are held by the pedals, a loose ring interior to the second-named disk and in the vertical plane of the sprocket-wheels and a removable ring interior to and 40 in the vertical plane of said loose ring for holding the latter in place, a clutch mechanism between the loose ring and second-named disk whereby a backward movement of the disk causes its clutch to frictionally engage 45 and lock the ring to the disks, and a brake and connections operated by the backward movement of the ring.

2. In a bicycle, the combination of companion disks fitted together sidewise one of 50 said disks fixed to the crank-shaft and the other disk having an open center, and both disks separated at their peripheries to form a channel or guide, a sprocket-wheel having its interior fitted to slide in said channel or 55 guide and a clutch mechanism between said wheel and disks, a ring loosely mounted on the disks and in the vertical plane of the sprocket-wheel, a stationary ring concentric with the loose ring and removably fitted to 60 one of the disks, for retaining the loose ring in place, means for connecting the loose ring with a brake device, and a clutch mechanism between the said ring and one of the disks whereby the rearward movement of the ring

causes the said clutch to hold the ring to the 65 disk in a locked condition while the sprocket-wheel continues in motion.

3. In a bicycle, the combination of companion disks fitted together sidewise and having interlocking annular flanges projecting 70 from their inner faces, and a peripheral channel or groove between their outer edges, a sprocket-wheel slidably fitted in said channel, a ring slidably fitted interior to one of said disks, a flanged screw-ring concentric 75 with and in the vertical plane of the slidable ring for holding it in place upon the other disk, oppositely-operating clutch mechanisms between the disks and sprocket-wheel and between one of said disks and the ring whereby 80 the wheel and disks rotate together when one of said clutch mechanisms is operating and the ring is stationary, and the disks and ring rotate together and in opposition to the wheel when power is applied to the ring and the 85 other clutch mechanism is operating.

4. In a bicycle, the combination of companion disks fixed together and one of which is fixed to the crank-shaft, a loose sprocket-wheel fitted between the outer edges of said 90 disks, a ring loosely fitted within the inner periphery of one of said disks and a removable locking-ring engaging the other disk and holding the loose ring in position, oppositely-operating clutch devices between the disks 95 and sprocket-wheel and between one of said disks and the loose ring and a brake and connections therefrom to the loose ring.

5. In a bicycle-brake, the combination of a disk rigid with the crank-axle, and having 100 a projecting threaded flange, a second disk opposing the first-named one, an open center sprocket-wheel mounted to rotate between said disks, a ring loosely mounted on the disks, a ring internally threaded and adapted 105 to screw into engagement with the projecting flange of the first-named disk, and having a flange or lip to retain the loose ring in place, a brake-shoe and a connection from the loose ring to said shoe, a roller-clutch between the disks and sprocket-wheel, whereby 110 they rotate together in one direction and one member moves freely on the other member when said other member is held against movement, or is moved in a direction opposite to 115 the rotation of its companion member, and a similar clutch between the disks and the loose ring, locking said disk and ring rigid on the backward movement of the former whereby the ring moves backward with the disk and 120 applies the brake-shoe.

In testimony whereof I have hereunto set my hand in presence of two subscribing witnesses.

CARL J. PIHL.
